UNITED STATES PATENT OFFICE.

JAMES R. FLETCHER, OF STAMFORD, CONNECTICUT, ASSIGNOR TO
THE YALE & TOWNE MANUFACTURING COMPANY, OF STAMFORD,
CONNECTICUT.

DOOR-KNOB.

SPECIFICATION forming part of Letters Patent No. 708,336, dated September 2, 1902.

Application filed June 10, 1902. Serial No. 111,042. (No model.)

To all whom it may concern:

Be it known that I, JAMES R. FLETCHER, of Stamford, in the county of Fairfield and State of Connecticut, have invented certain new and useful Improvements in Door-Knobs; and I do hereby declare the following to be a full, clear, and exact description of the invention, such as will enable others skilled in the art to which it appertains to make and use the same.

My invention relates to an improvement in door-knobs, and particularly to means for securing knobs to spindles, the object being to provide means whereby the spindle can be pushed into position within its knob-shank and locked there and be quickly and readily released without the employment of any tools or skilled labor.

With these ends in view my invention consists in a clamping-plate located within the shank of the knob and provided with a lug projecting through a slot in the knob-shank and a spring for normally holding said plate in a position to clamp the spindle.

In the accompanying drawings, Figure 1 is a view in elevation, partly in section, of my improvement. Fig. 2 is a similar view, enlarged, showing a spindle locked to the knob. Fig. 3 is a similar view showing the clamp in a position to permit the spindle to be moved in or out of the knob. Fig. 4 is a detached view of the clamp. Fig. 5 is a view of the inner end of the shank of the adjustable knob, showing the disk F removed, and Fig. 6 is a view of same with the disk in position.

A represents a spindle provided at one end with one or a series of holes for the passage of a pin a, which secures the fixed knob B to the spindle. If sufficient adjustment is not obtainable at the adjustable knob end of the spindle, as hereinafter described, additional adjustment can be secured at the fixed knob end by simply removing the pin and replacing it in another hole in the shank, although it will be found that in a great majority of instances the adjustment afforded by the adjustable knob will be ample.

The adjustable knob C is provided with a shank c, having a screw-threaded inner end by which it is secured to the knob. This shank has an angular opening at its outer

end which corresponds in size and shape to the cross-section of the spindle A and is provided in rear of said outer angular opening with a cylindrical bore b, within which the spindle-clamping devices are located. These devices comprise a clamping-plate D, preferably of disk shape, having an angular opening e therethrough, the said opening conforming in shape to the shape of the spindle A, but slightly larger than said spindle, so that when the disk is at right angles to the spindle the latter may be moved freely therein. The front end or wall d of the cylindrical bore b is arranged slightly oblique, as shown, the normal position of the clamping-plate D being parallel to and in contact with said oblique wall, so that the upper and lower walls of the slot or opening through the clamping-plate will engage and bite against the corresponding faces of the spindle and prevent any outward longitudinal movement of the latter. The clamping-plate D is provided on its periphery with a projecting lug or finger-piece d', which latter projects through a slot d² in the shank of the knob and rests in a position to be engaged by a finger. When this plate D is turned up to a vertical position, or a position at right angles to the shank of the knob, the bite on the spindle A is released, and the latter can then be adjusted longitudinally therein or the knob be adjusted longitudinally on the spindle, so as to bring the parts into their proper relative position.

Located within the bore of the shank of the knob C is the coiled spring E, which latter bears at one end against the clamping-plate and at its other end against the disk F, located within the inner open end of the shank of the knob and held therein by the lugs g, which latter are integral with the shank of the knob and turned inwardly, as shown, to lock the disk in place. This disk holds the spring under tension, and the latter yielding holds the clamping-plate in its oblique position.

With the parts thus constructed and applied it will be seen that the spindle can be freely moved inwardly, the clamping-plate yielding against the spring, but will resist all attempts to withdraw the spindle, owing to

the inclined position of the clamping-plate. By grasping the projecting lug d' of the plate D and turning same to a position at right angles to the shank of the knob the spindle 5 may be freely withdrawn from the knob C or the knob released from the spindle.

It is evident that changes in the construction and relative arrangement of the several parts might be made without avoiding my invention, and hence I would have it understood that I do not restrict myself to the particular construction and arrangement of parts shown and described; but,

Having fully described my invention, what 15 I claim as new, and desire to secure by Letters Patent, is—

1. The combination with a spindle, of a knob, a clamping-plate located within the shank of the knob and normally resting in an inclined or oblique position therein, the 20 said plate having a peripheral lug projecting through a slot in the knob-shank and a spring for yieldingly holding the clamping-plate in position.

25 2. The combination with a spindle, of a knob, a spindle-clamping plate located within the shank of the knob and provided with

a lug projecting through a slot in the knob-shank, and a spring for yieldingly holding said plate in a position to clamp the spindle. 30

3. The combination with a spindle, of a knob, a spindle-clamping plate located within the shank of the knob and provided with a lug projecting through a slot in said shank, a spring for yieldingly holding said plate in 35 a position to clamp the spindle, and a disk secured within the inner end of the shank and locking the spring within the shank.

4. In combination with a knob-shank, a movable clamping-plate carried in the shank, 40 a spring also carried in the shank which tends to throw the clamping-plate into the locked position, and means for compressing the spring and releasing the clamping-plate so that the spindle can be removed from the 45 shank.

In testimony whereof I have signed this specification in the presence of two subscribing witnesses.

JAMES R. FLETCHER.
